VEHICLE CONSOLE

Arliss L. Boothe, Indianola, Iowa, assignor to Auto Safety, Inc., Des Moines, Iowa, a corporation of Iowa

Filed Nov. 12, 1969, Ser. No. 20,047

Term of patent 14 years

Int. Cl. D12—14

U.S. Cl. D14—6

FIG. 1 is a perspective view of a vehicle console showing my new design;

FIG. 2 is a top plan view thereof;

FIG. 3 is an end elevation view thereof taken from the bottom end in FIG. 2;

FIG. 4 is an end elevation view thereof taken from the top in FIG. 2;

FIG. 5 is a side elevation view taken from the left side in FIG. 2; and

FIG. 6 is a side elevation view thereof taken from the right side in FIG. 2.

The element shown in broken lines is included for illustrative purposes only.

I claim:

The ornamental design for a vehicle console, substantially as shown and described.
